US0D1058849S

(12) **United States Design Patent** (10) **Patent No.:** **US D1,058,849 S**
(45) **Date of Patent:** **** Jan. 21, 2025**

(54) **REMOTE DEVICE FOR STERILIZATION CART**

(71) Applicant: **STERIS Corporation**, Mentor, OH (US)

(72) Inventors: **Dale J. Kitchen**, Chardon, OH (US); **John J. Lonczak**, Thompson Lake, OH (US); **Elizabeth Schwenner**, Euclid, OH (US); **Michael St. Onge**, Erie, PA (US); **Michael A. Varcho**, Mentor, OH (US)

(73) Assignee: **STERIS Corporation**, Mentor, OH (US)

(**) Term: **15 Years**

(21) Appl. No.: **29/911,792**

(22) Filed: **Sep. 8, 2023**

(51) **LOC (15) Cl.** **24-01**

(52) **U.S. Cl.**

USPC **D24/217**

(57) **CLAIM**

The ornamental design for a remote device for sterilization cart, as shown and described.

DESCRIPTION

FIG. 1 is a top, front, left perspective view of a remote device for sterilization cart (such as an accessory or a remote device for a sterilizing cart or similar equipment), showing our new design;

FIG. 2 is a top, front, right perspective view thereof;

FIG. 3 is a top, rear, right perspective view thereof;

FIG. 4 is a top, rear, left perspective view thereof;

FIG. 5 is a bottom, front, left perspective view thereof;

FIG. 6 is a bottom, front, right perspective view thereof;

FIG. 7 is a bottom, rear, right perspective view thereof;

FIG. 8 is a bottom, rear, left perspective view thereof;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The shade lines show surface contour and not surface ornamentation.

1 Claim, 14 Drawing Sheets
